WEATHER GUARD

George D. Fluke, Altoona, Pa.

Application May 23, 1933, Serial No. 672,474

1 Claim. (Cl. 20—68)

This invention relates to outside doors which are fitted with appliances designed to prevent rain, snow and air from entering under the door, and has for its primary object an improved weather guard adapted to be fitted to the outside of the door and designed to actuate such that rugs, carpets or other floor coverings are not disturbed by the guard when the door is opened.

Another object of the invention, is to provide a weather guard that clamps down firmly on the threshold plate such that it forms a perfect seal for the bottom of the door against rain, dust, snow, or wind, thus, in an efficient manner protecting the rooms inside from temperature variations.

A further object of this invention, is to provide a simple, rigid mechanism for actuating the guard such that when once properly installed on the door a minimum amount of maintenance is required.

A still further object of this invention, is to provide a case for the guard that not only properly shields the guard, but one that is attractive and can be placed on residence doors of all kinds without in any way distracting from the door's original design.

With these and many other objects in view, which will become more readily apparent as the nature of the invention is better understood, the same consists in the novel construction, combination and arrangement of parts as will be hereinafter pointed out, illustrated and claimed.

It will be quite readily understood by those skilled in the building art to which this invention belongs that the same is susceptible to some structural change or modification without departing from the spirit or scope of the invention; but a preferred and practical embodiment of the invention is shown in the accompanying drawing in which:—

Fig. 1 shows a plan view of an outside door positioned within the door casing, and having an improved weather guard applied thereto.

Fig. 2 is an elevational view of my weather guard applied to the door as illustrated in Fig. 1. The guard being shown down on the threshold plate the entire width of the door.

Fig. 3 shows a sectional view of the guard case, the weather guard and its position with reference to the bottom edge of the door.

Fig. 4 shows an outside door positioned within the door casing, the door being slightly ajar, illustrating the position of the operating rod when the door is so positioned.

Fig. 5 shows a partial elevational view of the

door illustrated in Fig. 4, and fully illustrates the position of the guard at the instant the door begins to open, the guard being automatically raised first at the edge adjacent the latch or lock, this feature being introduced for the primary purpose of clearing rugs or carpets adjacent the inside bottom edge of the door.

Fig. 6 shows an edge view of the parts shown in Fig. 5 of the drawing and further illustrates the clearance between the threshold plate and the edge of the guard at the lock edge of the door.

Fig. 7 shows a plan view of a door being swung away from the door casing a distance sufficient for the guard to be lifted free of the threshold plate the full width of the door.

Fig. 8 shows a partial side elevational view of the parts shown in Fig. 7 of the drawing, and illustrates the weather guard lifted the full length of the threshold plate, and the door being in position to be swung fully open.

Fig. 9 shows an edge view of the parts shown in Fig. 8 and further illustrates the guard free from the threshold plate.

Fig. 10 shows an enlarged sectional view of the weather guard, the casing surrounding the guard and the plunger mechanism used to actuate the guard.

Similar reference numerals refer to similar parts throughout the several figures of the drawing.

In carrying out this invention, no change is contemplated in the usual door construction or in the threshold plate positioned beneath the door, the invention being applicable to any and all doors whether made of wood or metal.

In carrying out this invention I provide a case 10, which is preferably made in two pressed metal pieces, the cover 11 adapted to fit into and cover the body 10. The case 10 is secured to the door 12 through the medium of a plurality of screws 13.

Within the case 10 the actuating mechanism designed to control the action of the guard, 14, is positioned.

The weather guard 14 is adapted to be carried in a pressed metal housing or carrier 15, which is slidably positioned in the case 10 as shown in Fig. 3 of the drawing.

The housing 15 is of inverted U-shape in cross section and is provided with a plurality of slots 50 cut in its upper edge 16 as clearly shown in Fig. 10 of the drawing. The slot 17 is engaged by the free end of a leaf spring 18, while the opposite end is secured to the inside top surface of the case 10 as shown in Fig. 2 of the drawing. The 55

means used to secure the end of the leaf spring to the case 10 is also employed to secure a bracket 19, the function of which will be described later.

The housing 15 is further provided with a slot 20 into which extends the end 21 of one arm of a bell crank shaped lever 22 which is fulcrumed on the case 10 through the medium of a screw, rivet or other support 23, as shown in Fig. 10 of the drawing. The underside of the said end 21 of the bell-crank lever 22 cooperates with an abutment carried by the housing 15, said abutment preferably being formed by bending inwardly one or both of the side walls of the housing 15 where the same is cut to provide the slot 20. Thus, upon depression of the end 21 of the bell-crank lever the housing 15 and the guard 14 are depressed. The end 21 of the bell-crank lever not only extends into the slot 20 but underlies a top portion of the housing 15. Consequently, upon elevation of the end 21 of the bell-crank lever the housing 15 and guard 14 are elevated.

The bell crank shaped lever 22 is further provided with a pin connection 24, which secures a bifurcated link 25 thereto. The link 25 has secured thereto an operating rod 27, which is slidably positioned in an open end bracket 28. Adjacent this bracket 28 on the rod 27 I position a washer 29, against which abuts a helical spring 30. In order that the load on the spring may be increased or decreased, I use a rotatable threaded nut 31 on the threaded portion of the rod 27. The threaded end of the rod 27 is further provided with an adjusting nut 32 which protrudes through the end 33 of the case 10. The position of this nut on the threaded rod 27 governs the action of the guard 14.

It will be further noticed from Fig. 10 that the helical spring 30 which has an abutment on the washer 29 which in turn rests against the bracket 28, exerts an effort at all times to lift the guard 14 together with its housing 15, away from the threshold plate, and the closing of the door, to which this guard is attached, serves to push the nut 32 into the case, actuating the bell crank 22 and thus forcing the weather guard 14 down on the threshold plate. When the door is opened, the spring 30 pushes the bell crank back into its elevated position and the guard is thus elevated or withdrawn from the threshold plate as indicated in Fig. 9 of the drawing.

The leaf spring 17 is made in duplicates, in order to make the guard reversible and is positioned within the case and slidably attached to the weather guard housing in such manner as to elevate the end of the guard housing as soon as

the door begins to open, thus in an efficient manner the guard is automatically raised clear of any rugs or floor covering that may be positioned near the door.

In order to firmly hold the guard case cover 5 in position, the screw 23 is adapted to pass through the guard into the door, there being a spacing element between the case and the cover in order to prevent the binding of the bell crank.

In order that the screw 32 may have an abutment in the door case, a screw 34 or similar means is located in the case in operative alignment with the operating rod 27.

The operation of this guard may be described as follows:

Let us assume that the door to which this guard is attached is closed. We would then have the condition as shown in Figs. 2 and 3 of the drawing. The rod 27 has thus pushed the bell crank 22 forward and the end 21 of the crank has carried the guard housing down the end 35 striking the threshold plate first, by virtue of the spring 18 holding the front up until finally forced down by the bell crank, overcoming the tension in the leaf spring 18. When the door begins to 25 open, the spring 18 lifts the forward end of the guard housing, causing the same to fulcrum around the foot 21 of the bell crank 22, the bell crank then lifting the guard housing vertically to clear the floor covering.

Having thus described my invention, what I claim and desire to be secured by Letters Patent is:

A weather strip attachment for hinged doors including a casing of transversely arched formation, means for securing the casing to a face of the door above the door sill, a weather guard slidably supported in said casing, said guard comprising a housing of inverted U-shaped formation having a weather strip fitted between and 40 projecting downwardly from the sides thereof, the crown of said housing being provided with a medial slot and a slot near one end, an abutment formed on the housing at the bottom of said medial slot, a housing supporting and elevating leaf spring carried by the interior of the casing and engaging in said slot near the end of the housing, a combined housing lowering and elevating lever pivoted in the casing and having a hook shaped end portion for entering the medial slot to alternately engage beneath the crown of the housing and bear down on the abutment, and a spring controlled rod connected with the lever and having one end extending exteriorly of the casing.

GEORGE D. FLUKE.
